HEATING AND AIR CONDITIONING
APPARATUS

Robert E. Daly, Bronxville, and Bernard Goerg, Scarsdale, N. Y., assignors, by mesne assignments, to American Radiator & Standard Sanitary Corporation, New York, N. Y., a corporation of Delaware

Application November 10, 1937, Serial No. 173,760

6 Claims. (Cl. 237—19)

Our invention relates to apparatus for supplying both heat and humidity to the air in room spaces and also for supplying hot tap water for the use of the occupants of such room spaces.

5 An object of our invention is to provide apparatus of the above type which is simple and inexpensive in construction and which operates in an improved and efficient manner.

The invention consists in the novel construction and combination of parts, to be more fully described hereinafter, and the novelty of which will be particularly pointed out and distinctly claimed.

10 In the accompanying drawings, to be taken as a part of this specification, we have fully and clearly illustrated a preferred embodiment of our invention, in which—

Fig. 1 is a fragmentary vertical section through a part of the basement and first floor of a house 20 and showing one embodiment of our invention as installed therein;

Fig. 2 is a vertical sectional view through a combined heat-exchange and humidifying device which forms a part of the embodiment of our 25 invention illustrated in Fig. 1;

Fig. 3 is a vertical transverse section taken on the line 3—3 of Fig. 2;

Fig. 4 is a horizontal or plan section taken on the line 4—4 of Fig. 2;

30 Fig. 5 is a fragmentary transverse vertical section taken on the line 5—5 of Fig. 4;

Fig. 6 is a fragmentary vertical section showing an outlet wall box for delivering humidified air into the room spaces; and

35 Fig. 7 is a plan section taken on the line 7—7 of Fig. 6.

Referring now in detail to the construction illustrated, it will be observed that we have shown our improved apparatus as installed in a building 40 which may be of any desired type; for example, the conventional dwelling house. A portion of the room spaces of the upper floor of this building is indicated by the reference character 10, and a portion of the basement space of such building is indicated at 11.

Within the room spaces 10 is located a suitable radiator 12 for heating the air therein, and there is also located in the room spaces an outlet box 13 for supplying humidified air to the room spaces.

50 Arranged within the basement space 11 is a conventional type of boiler furnace 14 connected to the radiator 12 by the usual supply and return mains 15 and 16, respectively. Any desired heating fluid may be used to transmit the heat gen-

erated in the boiler 14 to the radiator 12; for example, hot water or steam.

Arranged also in the basement space is a hot water storage tank 17 forming a part of a system for supplying hot tap water to the usual 5 bathrooms, lavatories, etc., in the room spaces. A hot water discharge pipe 18 is connected to the tank 17 and is adapted to be connected in a well known manner to the hot water taps, not shown. The usual cold water supply pipe for the hot 10 water system is indicated at 19.

A combined heat-exchange and humidifying device is also located in the basement space 11 and is indicated in general by the reference numeral 20. The device 20 is constructed as a single 15 separate unit and is connected to the boiler 14 by circulating pipes 21 and 22 so that the heating fluid from the boiler will circulate therethrough. The device 20 is also connected to the hot water storage tank 17 by circulating pipes 23 and 24 so 20 that the heating fluid circulating through the device 20 will be used to heat the water in the tank 17. In addition, the device 20 humidifies air and is connected by a duct 25 with the humidified air outlet box 13 in the room spaces 10 and thereby 25 supplies the humidified air to the room space.

Air for humidification may be supplied to the device 20 either from the outside atmosphere or from the room spaces of the building. The dot and dash lines 26 indicate a pipe connecting the 30 device 20 with the outside atmosphere. Water for humidification may be supplied to the device 20 by a suitable pipe 27 which, in so far as the broader aspects of my invention are concerned, may be connected to any suitable source of 35 water supply. In the drawings, we have shown the pipe 27 as connected to the hot water storage tank 17 so that the water for humidification will be warm or hot water.

In Figs. 2, 3, 4, and 5, we have shown the detail structural features of the device 20. The device 20 is constructed as a unit and comprises an enclosing casing structure 30, here shown to be rectangular in shape and suitably formed from sheet metal. The device 20 comprises a top wall 45 31, a bottom wall 32, side walls 33 and 34, and end walls 35 and 36. A vertical partition wall 37 extending from the top wall 31 to the bottom wall 32 and between the side walls 33 and 34, and a pair of spaced horizontal partition walls 50 38 and 39 extending from the vertical partition wall 37 to the end wall 36 and between the side walls 33 and 34; divide the interior of the casing structure into a heat-exchange space 40, a humidifying space 41, a blower space 42 and a space 55

43 for containing suitable electrical control devices for the apparatus.

Arranged within the heat-exchange space 40 is a hollow body, here shown to be in the form of a casting 45 which comprises a removable top wall 46, and a bottom wall 47 formed integral with side walls 48, 49, 50, and 51. From Fig. 2 it will be observed that the top wall 46, bottom wall 47, and side walls 48 and 49 of the casting 53 for humidified air, as will later appear. As can be seen from an examination of Figs. 3, 4, and 5, the casting 45 is of such a width that the side walls 50 and 51 thereof are arranged closely adjacent the side walls 33 and 34, respectively, of the casing 30 so that the air flowing through the passage 53 will not enter between these adjacent pairs of walls.

The upper part of the exterior surface of the side wall 49 is provided with a horizontally extending baffle or deflecting wall 55 which extends across the passage 53 and engages at its outer longitudinal edge the partition wall 37, and thereby forms a closed end wall for the passage 53.

The casting 45 is secured to the partition wall 37 by means of screws 56 extending through the wall 37 and through bosses 57, 58, and 59 projecting outwardly from the wall 49. The projecting bosses 57 and 58 are formed as a part of the baffle 55 and the boss 59 is spaced downwardly from the baffle and arranged centrally of the passage 53, as can be seen from an examination of Figs. 2 and 5.

An opening 60 is provided in the partition wall 37 at points just below the end or deflecting wall 55, which opening provides communication between the humidifying space 41 and the inlet end of the passage 53. The air entering the passage 53 through the opening 60 is humidified air, as will later appear, and this air will first strike the outer face of the wall 49 and then be deflected downwardly along such wall to the lower end thereof. The air will then flow horizontally along the wall 47, then upwardly along the wall 48, and upwardly and across the top wall 46 to an outlet connecting with the lower end of the conduit 25.

The interior surfaces of the walls of the casting 45 define a chamber 61 through which the heating fluid from the boiler 14 circulates. To this end, the walls 50 and 33 are provided with aligned openings near the top and bottom thereof, respectively, and pipe connections 62 and 63 are secured, respectively, within these openings to the wall 50 of the casting 45. The pipe connections 62 and 63 are connected, respectively, to the circulating pipes 21 and 22 previously described as being connected to the boiler. It will be noted at this point that in the embodiment shown, it is preferred that the fluid circulated through the chamber 61 by the pipes 21 and 22 will be water, and this is true both in a steam heating system and in a hot water system, for in the case of a steam system, the pipes 21 and 22 are preferably connected to the boiler at points below the waterline therein.

In order to promote heat transfer between the heating fluid in the chamber 61 and the air flowing through the passage 53, the interior surfaces of the walls 49, 47, and 48 of the casting are provided with heat absorbing fins 65, and the

exterior surfaces of these walls and also of the wall 47 are provided with heat dissipating fins 66. The fins 65 are arranged respectively opposite to the fins 66 so as to provide the most efficient transfer of heat. The fins 65 on any one wall are shown as being arranged parallel to one another and as extending in the general direction of circulation of heating fluid in the chamber 61. Likewise, the fins 66 of any one wall are arranged parallel to one another and extend in the general direction of air flowing through the passage 53. The exterior surface of the wall 49 is formed with an approximately circular pocket 68 arranged opposite to the opening 60, for a purpose which will appear more fully hereinafter.

Arranged within the chamber 61, and spaced from the walls of the casting 45, is a tubular heat-exchanger 69 for heating hot tap water which may be formed from a non-corrosive metal having high thermal conducting qualities. In so far as the broader aspects of our invention are concerned, the tubular heat-exchanger may be of any suitable type and construction. The type here shown is a coil formed by a spirally wound copper tube, and the coil is provided with pipe connections 70 and 71 at the ends thereof. The pipe connections 70 and 71 extend through aligned openings in the side wall 51 of the casting 45 and in the side wall 34 of the casing structure 30, and are connected, respectively, to the circulating pipes 23 and 24, the latter being in turn connected to the hot water storage tank 17 as previously described. Thus, the heat from the heating fluid within the chamber 61 serves both to heat the water of the hot water supply system in the tubular heat-exchanger or coil 69, and also to heat the humidified air flowing through the passage 53.

As stated previously, the opening 60 in the partition wall 37 serves as an air outlet opening 40 for the humidifying space or chamber 41. The chamber 41 is also provided with an inlet opening 73 extending through its defining partition wall 38. Included as a part of the humidifying chamber 41 is a means for adding moisture to the air as it flows therethrough between the inlet and outlet openings 73 and 60.

In so far as the broader aspects of our invention are concerned, this moisture-adding means may be of any suitable type and operation. In the construction shown, I have indicated this means as comprising a water spray device 75, comprising a nozzle 76 which ejects a fine stream of water toward the center of a target 77 carried by the outer end of a rod 78 adjustably secured to the nozzle casing. The distance between the target 77 and nozzle 76 may be varied to regulate the fineness of the spray, by lengthwise adjustment of the rod 78. The position of the target shown in full lines on the drawings is the mid position. The dotted line position of the target shown in Fig. 2 is the one occupied to produce maximum humidification. The pocket 68 permits the target to occupy the dotted line position. The water in striking the target is broken up and deflected back into the space or chamber 41, as shown. The nozzle 76 is connected to the water supply pipe 27 by means of a short section of pipe 80. A suitable solenoid valve 81 connected in the pipe 80 serves to control the flow of water to the nozzle 76, and a strainer 82 serves to remove solid particles from the water flowing to the nozzle.

The nozzle 76, target 77, and pipe 80 are supported in position by a detachable plate 83 form-

ing a part of the wall 36 of the casing structure. By detaching the plate 83, the nozzle 76 and target 77 may be readily withdrawn as a unit from the chamber for the purposes of inspection, cleaning, and repair. In order to facilitate the latter operation, the supply pipe 27 is provided with a coiled section 34 which permits the required movement of the nozzle into and out of the chamber 41 without breaking the pipe connections.

Arranged within the blower chamber 42 is a motor driven blower, indicated by the reference character 85. The blower may be of any suitable type, but is here shown as being one of the impeller type having an inlet 86 connected to an opening 87 in the outer wall 36 of the casing structure and having an outlet 88 extending through the inlet opening 73 of the chamber 41.

Secured to the outside of the enclosing casing structure 30 and communicating with the inlet opening 87 is an extension casing 89 in which is located a removable filter 90 which serves to eliminate dust, dirt, and the like, from the air entering the blower. The extension casing 89 may be provided with an inlet opening 91 communicating directly with the ambient air in the basement, and it also may be provided with an opening 92 connected to the outside atmosphere by the pipe 26, indicated in dot and dash lines. Instead of the pipe 26 being connected to the outside atmosphere, it may be connected to any other desired space, for example, the room space 10. A detachable plate 93 forms a part of the upper wall of the extension casing and may be readily removed for the purpose of replacing the filter 90.

In the operation of the construction shown, the chamber 41 is completely filled by a finely divided mist or fog from the spray nozzle 76, and the air flowing through the chamber from the blower absorbs a portion of the water and entrains therein some of the unabsorbed fog or mist. The partially humidified air with the mist entrained therein flows into the passage 53 through the opening 60 and will first strike the highly heated surfaces in and surrounding the pocket 68, and will then flow downward along the passage 53 and engage the highly heated finned outer surfaces of the walls 49, 47, and 48. As the air flows through the passage 53 and its temperature is increased by contact with the outer surfaces of the casting 45, the moisture absorbing capacity of the air is increased, which will promote the evaporation of the mist in suspension in the air. Further heating of the air by the walls of the casting serves to superheat and temper the humidified air so that such humidified air will not create discomfort when introduced into the room space through the grilled outlet opening of the box 13, and so that undue condensation will not occur at the outlet of the duct.

Within the lower part of the passage 53 is arranged a suitable drain opening 94 which extends through the bottom wall 32 and serves to conduct away any relatively large particles of water carried over into the passage 53 and not evaporated. Unevaporated water in the chamber 41 flows into the passage 53 through the opening 95 in the wall 37 and will also pass to the drain through the opening 94. The pocket 68 arranged opposite the opening 60 and coaxially with the target 77 forms a unique means for quickly heating the moisture-laden air as it enters the passage 53, and thereby promotes the quick absorption of

moisture by the air. The pocket 68 provides for the location of the target 77 as close to the heating surfaces as possible and thereby serves to minimize condensation of the moisture in the air stream and on the unheated walls adjacent to the spray. The fins 65 and 66 also aid materially in the efficient humidification of the air and the effective superheating and tempering of the humidified air as it flows through the passage 53.

In Figs. 6 and 7 it will be observed that the outlet box 13 is arranged within the lower part of a room partition wall 97 and is in the form of a casing 98 having an inlet opening 99 connected to the upper end of the duct 25 and having an outlet opening 100 communicating through an opening in the wall 97 with the room space. The outlet opening is provided with a detachable grille 101 through which the humidified air flows and the interior side of the grille is provided with a plurality of deflector plates 102 which serve to deflect the air flowing through the opening 100 upwardly into the room. The area of the interior of the casing 98 adjacent the inlet opening 99 is restricted by an inclined top wall 103 and by walls 104 and 105 arranged at opposite sides of the opening; and the walls 103, 104 and 105, as well as the remaining adjacent inside surfaces of the casing are covered with a suitable sound absorbing material, indicated at 106. This structure serves to eliminate the usual drumming noise incident to the flow of air through a hollow box.

From the above, it will be appreciated that we have provided a simple and inexpensive form of apparatus which performs the triple purpose of heating the air in the room spaces, of supplying humidity to such air, and of supplying hot water to the hot water taps for personal use. It will also be observed that an important part of this inexpensive structure is the unitary device 20 which operates both as an external hot water heater and also as a humidifying and tempering means for humidified air. In prior art systems for supplying humidifying air, there has always been provided a separate tempering coil at the down stream side of the humidifier. In the prior art hot water heating systems there has always been provided a separate heat-exchanger for heating the hot water. The usual separate tempering coil and the separate heat-exchanger has been eliminated in the present apparatus, as we provide a single unitary device for performing these two functions. Considered in one sense, it might be said that we utilize the heat which is normally lost to the atmosphere in the hot water heaters of the prior art to perform the function of tempering and superheating the humidified air.

According to one aspect of our invention, the apparatus described above may be considered as comprising the combination of a heating system, a hot water supply system, an air humidifying system, and a single means connected into all three systems and serving to heat the hot water and to temper and superheat the humidified air. The heating system comprises the boiler 14 containing the heating fluid, the radiator 12, and the circulating pipes 15 and 16 connecting the boiler and radiator. The hot water supply system comprises the hot water storage tank 17, the cold water supply main 19, and the hot water pipe 18. The humidifying system comprises the humidifying chamber 41, the blower 85, the outlet box 13, and a conduit means connecting the

chamber 41 and box 13. The above-mentioned single means is the heat-exchange device 20 comprising walls defining three separated passages arranged in heat-exchange relation with one another and respectively connected into the three systems. The first passage is the chamber 61 connected by the circulating pipes 21 and 22 into the boiler. The second passage is the coil 69 connected by the circulating pipes 23 and 24 to the tank 17. The third is the passage 53 forming a part of the conduit means connecting the humidifying chamber 41 and box 13.

We claim:

1. In apparatus of the character described, the combination of a boiler containing a fluid for heating room spaces; a storage tank for hot tap water; heat-exchange means arranged exteriorly of said boiler for heating said tap water by said heating fluid and including walls defining a chamber connected to the boiler to receive the heating fluid therefrom, and a tubular heat-exchange device arranged within said chamber with the heating fluid contacting the exterior surfaces thereof and being connected to said 25 storage tank so that the tap water flows through the interior of said device; a humidifying casing; a water-atomizing device in said casing; and blower means providing for the flow of a stream of air serially through said humidifying chamber, 30 over the exterior surface of one of said defining walls, and then into the room spaces.
2. In apparatus of the character described, the combination of a system for supplying heat to room spaces and including a boiler containing 35 a fluid for heating said spaces; a hot water supply system; a heat-exchange device for heating the water of said last-named system by said heating fluid and comprising walls defining a closed chamber separated from said boiler and having 40 inlet and outlet pipe connections connected to the boiler so that said heating fluid circulates therethrough, a coil arranged entirely within said chamber and having pipe connections for connecting said coil to said hot water supply system, walls spaced from the exterior of said chamber-defining walls to provide a passage for air 45 having one side thereof defined by the exterior surface of said chamber walls; an air-humidifying chamber having an air inlet and an air outlet, the outlet being connected to one end of said passage; conduit means connecting the other end of said passage with the room space; and means providing for the flow of air serially through said 50 humidifying chamber, said passage, and said conduit means.
3. A combined external water heater and humidifier for use with heating boilers for building spaces comprising a housing adapted to be located externally of the boiler and having pipe 55 connections therewith providing for the circulation of the boiler heating fluid therethrough; a tubular heat exchanger arranged within said housing and having pipe connections at its ends providing for the circulation of water for tap use therethrough; a casing enclosing at least a portion of said housing and defining therewith a passage for the flow of air having an inlet and an outlet and adapted to be connected at its outlet to the building space; and spray means for 60 adding moisture to the air at the inlet end of said passage.

4. The combination with a boiler containing a fluid for heating room spaces, and a water heater arranged externally of said boiler and comprising a hollow housing, pipes connecting the housing with the boiler and providing for the circulation of the boiler fluid through said housing, and a pipe coil arranged within said housing and including end pipe connections extending through said housing and adapted to connect said coil into a domestic water supply system; of a casing enclosing said water heater and including defining walls arranged in spaced relation to the exterior surface of said housing to define therewith a passage for air having inlet and outlet ends; a blower carried by said casing and providing for the flow of air through said passage; means for introducing a stream of finely divided water into the air as it enters said passage; and a conduit adapted to convey the humidified and tempered air from the outlet end of said passage into the room space.

5. A unitary attachment for use with boilers and adapted to be arranged externally thereof, and comprising a hollow housing having pipe connections adapted to be connected to a boiler 25 to provide for the circulation of the boiler heating fluid therethrough; a pipe coil within said housing and having its ends extending through said housing and adapted to be connected to a hot water supply system; a casing enclosing said 30 housing and including walls spaced from the exterior surface of said housing to define therewith a passage for air having inlet and outlet ends; said casing also including walls defining a humidifying chamber having an outlet directly 35 communicating with the inlet end of said passage, and including walls defining a blower chamber having an outlet communicatively connected with the humidifying chamber; a blower within said blower chamber and providing for 40 the flow of air serially through said humidifying chamber and said passage; and water atomizing means in said humidifying chamber.

6. In apparatus of the character described, the combination with a boiler containing a fluid for 45 heating room spaces, of a unitary externally arranged attachment for the boiler and operable to heat water for domestic use and to supply humidified air to the room spaces and comprising walls defining a hollow housing, pipe connections 50 connecting the interior of said housing to said boiler and providing for the circulation of the boiler fluid through said housing, a tubular heat-exchange device arranged within said housing with the external surfaces thereof in thermal 55 contact with the boiler fluid and having end pipe connections extending through said housing and adapted to be connected into a hot water supply system, walls defining a casing enclosing said housing and spaced from said housing walls to 60 provide an air passage therebetween having inlet and outlet ends, blower means carried by said casing and providing for the flow of air through said passage, and means within said casing for introducing a stream of finely divided water into 65 the air as it enters said passage; and conduit means connected to the outlet end of said passage and adapted to connect said unitary attachment with said room spaces.
